US00D579414S

(12) **United States Design Patent**
Münch et al.

(10) **Patent No.:** US D579,414 S
(45) **Date of Patent:** ** Oct. 28, 2008

(54) **E-CONNECTOR**

(75) Inventors: **Markus Münch**, Coswig (DE); **Florian Zschoge**, Dresden (DE)

(73) Assignee: **Solar Watt AG**, Dresden (DE)

(**) Term: **14 Years**

(21) Appl. No.: **29/291,016**

(22) Filed: **Aug. 9, 2007**

(51) **LOC (8) Cl. 13-03**

(52) **U.S. Cl. D13/133; D13/154**

(58) **Field of Classification Search** D13/133,
D13/154, 184, 199; 136/244, 256; 439/66,
439/62, 65, 82, 83, 567, 636, 660, 682, 856,
439/857, 862
